UNITED STATES PATENT OFFICE.

DANIEL McFARLAN MOORE, OF NEWARK, NEW JERSEY, ASSIGNOR TO MOORE ELECTRICAL COMPANY, OF NEW YORK, N. Y., A CORPORATION OF NEW YORK.

VACUUM-TUBE LIGHTING.

No. 895,485.

Specification of Letters Patent.

Patented Aug. 11, 1908.

Application filed April 2, 1906. Serial No. 309,282.

To all whom it may concern:

Be it known that I, DANIEL McFARLAN MOORE, a citizen of the United States, and a resident of Newark, in the county of Essex and State of New Jersey, (with post-office address 52 Lawrence street,) have invented certain new and useful Improvements in Vacuum-Tube Lighting, of which the following is a specification.

10 My invention relates to those systems of electric lighting in which the light is obtained from a luminous column of conducting gas or vapor inclosed in a translucent, non-conducting tube projecting from a protective case or envelop in which the conducting terminals of said tube are located, together with the source of high potential energy required for exciting the gas or vapor to luminosity. In this system of illumination, the translucent tube containing the gas or vapor is ordinarily made many feet in length and is extended over or through the whole space to be illuminated so as to give a practically uniform illumination.

25 In the case of apartments or interiors of ordinary dimension, that is to say, interiors less in dimensions than halls or arenas designed for very large gatherings of people, a single tube will serve for the illumination of 30 the entire inclosed space.

For office buildings, apartments or dwelling houses, each interior room or space can be readily lighted by a single tube, whose length in any case would obviously depend 35 upon the size of the room or in some cases upon the degree of illumination desired, as for instance, where it is desired to increase the illumination by carrying the tubing backward and forward through the interior 40 space.

In the practice of this method or system of illumination, it is usual to employ as the source of energy, the high potential derived from a suitably wound transformer, all of 45 whose high potential windings and connections are located in the protective case or envelop and there directly connected to the conducting terminals or electrodes of the tube, and as will be obvious, such high potential winding should in any case be accommodated to the length of tube and hence resistance of the gas or vapor path extending between the tube terminals.

The object of the present invention is to

55 cheapen the total cost of installation in those cases where it is desired to use a number of tubes illuminating different areas or spaces and of different lengths or of the same lengths.

60 A further object of the invention is to provide means whereby the lighting may be conveniently and safely controlled by turning the light on or off in the different tubes independently of one another.

65 To these ends, the invention consists substantially in an improved system or apparatus for electrical illumination comprising a series of translucent tubes containing a luminous gas or vapor and all extending from a common center or base of tube distribution 70 at which point their conducting terminals are all housed in a protective case or envelop containing a transformer, whose high potential side comprises a number of secondaries 75 connected respectively to said tubes and each adjusted to the length of tube to which it is connected.

75 The invention further consists in the provision for each of said tubes, of an oil switch located in the said protective inclosure and placed in the electric circuit between the secondary and the tube supplied thereby.

80 The invention consists further in the improved combinations of apparatus herein-after more particularly described and then 85 specified in the claims.

85 In the accompanying drawings, Figure 1 is a general side elevation and partial section showing in skeleton or diagrammatic fashion a tube center with the associated appliances. 90 Fig. 2 illustrates diagrammatically the application of my invention to the illumination of spaces on different floors of a building or structure.

95 Referring to Fig. 1, the tubes of glass containing the luminous gas or vapor are marked 1. In this figure the portions of said tubes near the center of distribution only are shown. The other portions extend away in any desired direction and to and over any desired spaces and are of any desired length requisite for reaching the space to be illuminated and for properly illuminating the same.

100 2 indicates the conducting terminals by means of which the gas or vapor contents of the tubes receive electric energy. Said terminals may be internal or external electrodes 105 as well understood in the art. They are lo-

cated within a suitable protective case or envelop 3, which may be made of iron lined with asbestos or constructed in any suitable manner to protect the contents against accidental contact and to be fire-proof and to answer to the requirements of the rules of fire underwriters.

4 indicates the transformer, the case of which is shown in full lines, while its windings are indicated diagrammatically by dotted lines, 5 being the primary or low potential side of said transformer, while 6 indicates a series of high potential secondary windings connected respectively to the terminals 2 within the casing 3 as shown. The potential of each said primary is adjusted to the length of the particular tube 1 to which it is connected, it being well understood that the longer the tube the higher ordinarily should be the potential of the electric energy supplied thereto.

Three tubes and three corresponding secondaries 6 are shown, but it is obvious that a larger number of secondaries and tubes 25 might be employed. It is likewise obvious that more than one primary might be used or more than one complete transformer.

In the connection between each tube and its secondary 6 is located an oil switch 7, by means of which each tube may be lighted or extinguished at will. Said oil switch is likewise located in the protective inclosure 3. It may be actuated by any desired mechanism and if desired the actuating handle or controlling device, if properly insulated, may extend or be located outside of the casing 3.

Referring to Fig. 2 I show diagrammatically a series of four tubes applied to the illumination respectively of four different floors in a building. Said tubes extend from the common tube center located as near as possible at the center of said floors and said tubes, if required to give the same amount of illumination on their respective floors, would 45 obviously require to be of different length, or it might be that on each floor a different amount of illumination would be required from that demanded on other floors. In any case the potential of each secondary connected to any tube at the center of tube distribution would be adjusted to the length of that tube. Obviously, a still larger number of floors might obtain their light from the same center of tube distribution or a larger number of tubes might extend from the same center and a number be used on the same floor for illuminating different rooms or apartments, the length of each tube being adjusted to the size of the interior to be lighted.

60 By my invention, I am enabled to apply the vacuum tube system of lighting to buildings and to greatly cheapen the total cost of installation when said tubes are operated from transformers and require to be of different length.

What I claim as my invention is:

1. An apparatus for illumination by translucent tubes containing a luminous gas or vapor rendered luminous by electric energy and comprising a series of tubes of different length extending from a common center of tube distribution and having their conducting terminals or electrodes housed in a protective case or envelop combined with independent sources of high potential energy, 70 connected respectively to the tube terminals within said casing and each adjusted to the length of tubing supplied.

2. In an apparatus for electric lighting by luminous gas or vapor contained in translucent tubes, the combination of a series of transformer secondaries, a protective casing inclosing the same at a common center of tube distribution and translucent tubes having conducting terminals or electrodes located 80 in said casing and connected respectively to different secondaries, the non-conducting translucent portions of said tubes being extended from said tube center in different lengths of tubing to the spaces or interiors to 90 be lighted.

3. In an apparatus for electrical illumination by a gas or vapor contained in translucent tubing, the combination of a multiplicity of tubes having their conducting terminals located at a common base or center of tube distribution, a protective casing in which said terminals are located, a source of high potential energy to which the tube terminals or electrodes are connected in said 95 casing and oil switches in the connections in said casing between the high potential source and the tube terminal, as and for the purpose described.

4. In an apparatus for electric lighting by 105 a gas or vapor inclosed in translucent tubing, the combination of a transformer having a series of secondaries, a protective casing inclosing said secondaries, and a series of tubes having their terminals connected within said 110 casing to said secondaries respectively and having their translucent non-conducting portions extending from said casing as a tube center of distribution to the areas or spaces to be lighted as and for the purpose described.

5. In an apparatus for electric lighting by 120 a gas or vapor contained in translucent tubing, the combination of a multiplicity of tubes radiating from a common center or base of tube distribution and having their conducting terminals housed in a protective case or envelop, and sources of high potential for said tubes also located in said envelop and therein connected to the terminals 125 of said tubes.

6. In a system of vacuum tube lighting, the combination with a multiplicity of tubes having their conducting terminals located at 130 a common base or center of tube distribu-

tion, a protective case or envelop for said tube terminals and a potential raising converter located in said casing and supplying high potential energy to the terminals of said tubes.

7. The combination of a terminal danger proof box and a multiplicity of vacuum lighting tubes radiating therefrom as from a tube center of distribution, each of said tubes be-

ing provided with conducting terminals located within said danger-proof box.

Signed at New York in the county of New York and State of New York this 30th day of March A. D. 1906.
